UNITED STATES PATENT OFFICE

2,096,320

METHOD AND APPARATUS FOR SAMPLING
RODS AND WIRES

Ralph Coleman, Lorain, Ohio, assignor to National Tube Company, a corporation of New Jersey

Application August 26, 1936, Serial No. 98,033

5 Claims. (Cl. 90—11)

This invention relates to a method and apparatus for procuring sample chips from specimens such as, for example, rods and wires.

Prior to my invention sample chips for analysis were obtained by gripping the wire or rod in a lathe and turning chips from the periphery of the wire or rod. However, this method was not only slow and consequently costly but also unsatisfactory in that in many instances sample 10 chips from the entire cross-section could not be obtained. The present invention seeks to overcome these disadvantages. Better sample chips can be obtained in that they are taken from the entire cross-section and a considerable saving 15 both in time and expense is made possible by its use.

One of the objects of the present invention is the procuring of suitable sample chips from an entire cross-section at a rate of speed not hitherto possible.

The foregoing and other objects will be apparent after referring to the drawing, in which:

Figure 1 is a top plan view of a preferred embodiment of my device for procuring sample 25 chips from a specimen.

Figure 2 is a longitudinal view of same, partly in section.

Figure 3 is an end elevation.

Figure 4 is a sectional view on the line IV—IV 30 of Figure 2.

Referring more particularly to the drawing, the numeral 10 designates a U-shaped base of a device to be attached to the table of a standard milling machine (not shown) by clamps or other 35 suitable means. The base 10 has closed ends 12 and 13 which are provided with alined openings 14 and 15 respectively. A screw-threaded shaft 16 is journaled in the alined openings 14 and 15 of the base 10 by a pin 16 and collar 17. This 40 shaft 16 extends through the end 13 of the base 10 and is provided with a collar 18, which is secured thereto by a pin 19. This end of the shaft 16 is also provided with a thumb-screw 20. Secured to the thumb-screw 20 is a crank handle 45 21. A guide member 22 is suitably secured to the end 12 of the base 10, and is provided with an opening 22a having a bushing 23 secured therein by a screw 24. A feed block 25 is provided with a semi-cylindrical screw-threaded recess 26 for 50 engagement with the screw-threaded shaft 16 and a slot 27 in the side thereof cooperates with cover plate 31 to hold the feed block 25 in engagement with the shaft 16. The feed block 25 has an opening 28 in its upper end which has a bushing 55 29 secured therein by a screw 30. Various sizes

of bushings 23 and 29 may be provided to accommodate various sizes of rods or wires.

The base member 10 is also provided with a cover member 31 having a slot 32 to provide a guideway for the feed block 25. This cover 31 is removably secured to the base 10 by thumb-screws 33 or other suitable means.

Secured in the arbor of the milling machine are two or more circular saw blades 34 having their teeth 35 in staggered relation. The number of circular saws 34 may be varied according to the diameter of the specimen from which it is desired to obtain sample chips.

A length of wire or rod 35 from which it is desired to obtain sample chips is inserted in the 15 bushing 23 and the guide block 25 is moved to the desired position, depending upon the length of the wire or rod 35, and the opposite end of the wire or rod is placed therein and secured by the screw 30. The milling machine table is adjusted 20 so that the center line of the wire or rod 35 is in the same plane as the center line of the arbor and the longitudinal axis of the wire is at a right angle to the axis of rotation of the saw arbor. Then the base 10 is moved to bring the 25 end of the bushing 23 approximately $\frac{3}{2}$ inch from the periphery of the saws 34. The speed of the rotation of the saws is then regulated according to the carbon content of the steel in order that the chips may not be burned by the 30 cutting operation. The speed at which the sample is fed to the saws by the crank 21 is governed by the grade of steel of the wire or rod and the quality of the chips desired.

While I have shown and described a specific 35 embodiment of my invention, it will be understood that I do not wish to be limited exactly thereto, since various modifications may be made without departing from the scope of my invention, as defined by the following claims.

I claim:

1. A method of procuring sample chips from a specimen comprising obtaining a specimen and feeding said specimen endwise against a saw, the longitudinal axis of said specimen being at substantially a right angle to the axis of rotation of said saw.

2. A method of procuring sample chips from a specimen comprising obtaining a specimen and feeding said specimen endwise against the teeth 50 of a saw, the longitudinal axis of said specimen being at substantially a right angle to the axis of rotation of said saw, said axis and the axis of rotation of the saw being in substantially the same plane.

40

45

50

55

3. A method of procuring sample chips from a specimen comprising obtaining a specimen and feeding said specimen endwise against a saw, the longitudinal axis of said specimen being at substantially a right angle to the axis of rotation of said saw, the speed of rotation of said saw and the rate of speed at which the specimen is fed to the saw being so regulated as not to burn the samples so obtained.
5. In combination with a milling machine, an attachment for procuring sample chips from a specimen comprising a saw, said saw consisting of at least two circular saws placed together, the teeth of said saws being staggered, and means for feeding a specimen endwise against the teeth of said saw.
10. An apparatus for procuring sample chips from a specimen comprising a saw, said saw consisting of at least two circular saws placed to-

gether, the teeth of said saws being staggered, and means for feeding a specimen endwise against the teeth of said saw.

5. In combination with a milling machine, an attachment for procuring sample chips from a specimen comprising a saw, said saw consisting of at least two circular saws placed together, the teeth of said saws being staggered, and means for feeding a specimen endwise against the teeth of said saw.
